VENDING MACHINE

Glen G. Barnard, Denver, Colo.

Application July 6, 1937, Serial No. 152,073

6 Claims. (Cl. 194—69)

This invention relates to vending machines operable in response to insertion of a coin of certain dimensions.

Objects of the invention are to provide a device of the class described which (a) is adapted to contain a supply of and deliver for a single coin and by a single operation a plurality of articles of different shapes and sizes but which are designed for conjoint use such as a paper cup and a predetermined number of medicinal tablets to be taken with water in such cup; (b) shall be compact, convenient, simple, economical and efficient in construction and operation; (c) shall be efficiently safe-guarded against "milking", i. e. unauthorized extraction of contents; (d) shall at all times show at a glance the number of tablets remaining in the container and (e) shall protect the contained tablets from damage or atmospheric deterioration.

With these and other objects in view, all of which will more fully hereinafter appear, my invention comprises certain novel constructions, combinations and arrangements of parts as will be hereinafter fully described and claimed and as illustrated in the accompanying drawings in which like characters of reference indicate corresponding parts throughout and in which

Fig. 1 is a front elevation of my vending machine.

Fig. 2 is a right side elevation of Fig. 1.

Fig. 3 is an elevation view of the rear of the housing and contained mechanism as viewed when opened for servicing, the back of the housing being viewed at an angle and somewhat foreshortened.

Fig. 4 is a horizontal section on line 4—4 of Fig. 3.

Fig. 5 is a horizontal section on line 5—5 of Fig. 3.

Fig. 6 is a section on line 6—6 of Fig. 3.

Fig. 7 is a view like Fig. 6 but illustrating the parts in position at completion of inward stroke of the plunger with single cup dropped.

Fig. 8 is a section on line 8—8 of Fig. 3.

Fig. 9 is a section on line 9—9 of Fig. 3.

Fig. 10 is a fragment illustrating position of certain parts when dropping a tablet at completion of inward stroke of the plunger.

Fig. 11 is a fragment illustrating position of coin and certain parts during the inward stroke of the plunger.

Fig. 12 is a fragment illustrating the catch in position to prevent unauthorized inward movement of the plunger.

Fig. 13 is a detail perspective view of the plunger element complete.

The Figures 10, 11 and 12 are on a relatively enlarged scale.

My invention is designed for the vending of a paper cup and two medicinal tablets and will be described in terms of such construction and use though, obviously, the number of tablet-containing and dispensing units may be increased or diminished as desired in order to vend, with a single cup, the number of tablets desired for a standard dose.

My invention comprises a back 20, to be attached to a wall or other support in any suitable manner, not shown, to which back I attach a 15 housing 21 preferably by hinges 22 and lock 23. The principal part of the mechanism is mounted in and carried by the housing 21, a few parts being carried on the back 20 and thereon positioned to cooperate with certain parts carried 20 in the housing when the device is closed.

Exteriorly, the housing is provided with a cup-removing opening 24, a tablet removing opening 25, windows 26, a coin-chute housing 27 having a coin slot 28 therein, and a plunger bar 29 having 25 push button 30.

Interiorly of the housing and above the opening 25 I provide shelf 31 suitably supported on the walls of the housing and covering a coin box 33 having receiving chute 33a and slidably supported by flanges 33b on brackets 32. Gaskets 34, of rubber or other suitable material, for seating and sealing the lower ends of the tablet tubes, later described, are carried by shelf 31 which shelf is also provided with holes 35 and 36 aligned 35 between the gaskets and for the purposes hereinafter described.

Tubes 37, preferably of glass, normally have their open lower ends seated upon gaskets 34, the tops of the tubes being covered by caps 38, 40 the capped upper ends of the tubes having a loose sliding fit within cylindrical guides 39 depending from the top of housing 21. Resilient means, as springs 40 within the guides 39, are provided for normally holding the lower ends of the tubes 45 tightly against gaskets 34.

Bar 41 performs several functions, including holding the tubes in fixed interrelation, providing means by which the tubes may be lifted and cooperating with fixed guides hereinafter described, 50 for holding the tubes in proper alignment during reciprocation. This arrangement is conveniently accomplished by forming the bar 41 in two parts as clearly shown at Figs. 4, 8, 10, 11 and 12, and providing ridges 42, which may be molded with 55

- the tubes, between which the bar 41 engages the tubes 37. The two parts of the bar 41 are clamped together, with the tubes thus clamped between them, by suitable means, such as cleats 43 fastened to bar 41, by any suitable means, not shown. The bar 41 is provided with a suitable runway in which it vertically reciprocates when the tubes are raised and lowered, such runway being conveniently formed by members 44, projecting from the back 20, the end wall of the housing 21, guide 45 and cleats 46 and 47 attached, respectively, to the end wall of the housing and to guide 45.
- The tubes 37 are adapted to be loaded with tablets, indicated at 48, above which, freely slideable within each tube, is a plug 49, having a conical base 50, for the purpose hereinafter described and having characters upon the sides of the plug visible through windows 26 when the tablets within the tubes have been reduced to or below the level of the windows, all as clearly illustrated at Fig. 9.
- A bent coin-chute 51 is provided within the housing 21 leading from the coin slot 28 to the hereinafter described point at which the coin is received for operative purposes.
- Also within housing 21 and above opening 24, I provide a compartment for an inverted nest of cups as illustrated in Figs. 3 to 7 inclusive. The guide 45 forms one wall of this chamber and an opposed guide 52 is positioned oppositely on the side wall of housing 21. The front wall of housing 21 forms a third guide 53 while a fourth guide 54 is carried by the back 20. Guides 45 and 52 are opposite and spaced apart slightly in excess of the diameter of the periphery of the rims of the cups and the guides 53 and 54 are similarly spaced when the device is closed so that in closed position of the device the four guides form a runway in which the inverted nest of cups may move freely up and down. Normally the nest of cups rests on a portion of the plunger assembly as illustrated at Figs. 3 and 4 and as hereinafter more fully described.
- Slide 55 is provided beneath the tablet discharge mechanism to slide the dropped tablets forward toward opening 25 so that they may be easily reached manually through said opening. This slide is preferably attached, by any suitable means not shown, along its lower edge, to the bottom of the housing and along its side edges to the wall of the housing adjacent hinges 22 and partition 79 which separates the two chambers of the machine.
- The plunger assembly is a complete, rigid member shown in perspective in detail at Fig. 13 and comprises the push button 30, plunger bar 29, wings 56, semi-circular plate 57, runners 58 and runner 59, wedges 60, spring post 61 and lug 62. The runners 58 slidably rest on shelf 31 and runner 59 slidably rests on bracket 63 carried by the side of the housing.
- Plunger bar 29 is notched as at 64 and bifurcated to form a coin receiving slot 65 and the bifurcation continues to the bottom of the bar 29 and backwardly therefrom forming recess 66, such downward extension and recess being provided for the accommodation of member 67 which performs the combined function of a coin stop and safety catch. Member 67 is pivoted between the bifurcations as at 68 and is notched as at 69, a stop 70 being mounted between said bifurcations and within said notch 69 to limit the downward movement of the inner end of the member 67. The outer end of member 67 is provided with

a hook 71 adapted to engage in hole 35 under certain conditions and resilient member 72 is provided for forcing hook 71 into hole 35 whenever hook 71 is over hole 35 and there is no coin of the required size in slot 65.

Spring 73 is attached, by any suitable means indicated at 74, to the front wall of housing 21 and to spring post 61 whereby to retract the plunger assembly to and resiliently hold it in forward, inoperative, position.

The tubes being supplied with tablets 48 surrounded by the plug 49 as illustrated at Fig. 9 and a nest of cups being placed on plate 57 as illustrated in Figs. 3 and 6 and the device being closed and the plunger assembly in forward, inoperative, position all as illustrated in Fig. 4, the operation is as follows:

A coin of the dimensions for which the machine is constructed, preferably a nickel, is inserted in slot 28 and drops through chute 51 into slot 65 coming therein to rest on member 67 all as illustrated at Fig. 8. Pressure is then exerted on button 30 forcing the coin against bar 41. It will be noted that the parts are so proportioned that the coin will contact the lower front edge of bar 41 at a point on the edge of the coin above its horizontal diameter as it thus rests upon member 67 so that the pressure on the button 30 will cause the coin to act as a cam and lift bar 41 and, therewith the tubes 37, overcoming the weight of the tubes and the pressure of springs 40. The bar 41, with the tubes, will be lifted to the height of the top of the coin and the parts are so proportioned that the vertical distance to the top of the coin from the point on the coin where it first contacts bar 41, is slightly greater than the thickness of one of the tablets in the tubes so that when bar 41 is raised sufficiently to permit the coin to pass thereunder, the bottoms of the tubes will have been raised above the gaskets 34 a distance sufficient to expose one tablet under each tube and permit the same to be slid from under the tube. The pressure being continued, the coin slides beneath and supports bar 41 with the attached tubes and wings 56 contact the exposed tablets and push them from under the tubes and coincidentally support the remaining tablets within the tubes. When the stroke is completed the exposed tablets have been pushed to the rear and drop (as illustrated at Fig. 10) on either side 50 receiving chute 33a and onto guide 55 which causes the tablets to slide forward toward opening 25 through which they may be manually reached and removed.

Coincidentally, when the plunger assembly reaches the end of its inward stroke the inertia of the coin will cause it to roll down along the inclined end 67a of member 67 and into coin receiving chute 33a and thence into coin box 33. Should the inertia fail to thus drop the coin, it will be shoved off into the chute 33a by bar 41 when it contacts said bar on the return stroke of the plunger assembly responsive to the pull of spring 73.

Coincident with the above described tablet dropping operation, the plate 57 is moved out from under the nest of cups but during this movement wedges 60 enter the space between the rims or beads of the two lowest cups thus separating the bottom cup from the balance of the pile by lifting said next-to-the-bottom cup and those thereabove, leaving the bottom cup resting on shelf 57 until the plunger assembly reaches the end of the inward stroke at which time the semi-circular inner edge of shelf 57 will have cleared 75

the rim of the bottom cup and the cup will drop to position shown in Fig. 7.

When the dropping of the tablets, cup and coin have been completed, as above described, 5 the pressure on button 30 is released and spring 72 will retract the plunger assembly to normal, inoperative position ready for the next operation it being obvious that shelf 57 will move under the nest of cups while the wedges 60 are still 10 supporting them so that when the wedges are retracted from contact with the cups the cups will drop onto and be supported by shelf 57 and, likewise when wings 56 are retracted from beneath the tiers of tablets those tiers will drop 15 onto the gaskets and, practically coincident therewith, the wings 56 will be retracted from under the tubes and the tubes will drop onto the gaskets, enclosing the tablets and sealing them from the atmosphere.

20 It will be noted that the outside of hook 71 is rounded and the forward edge of hole 35 is inclined so that during retraction of the plunger assembly the hook 71 will slide over hole 35.

In case an effort be made to "milk" the machine 25 by stopping the retraction of the plunger unit when the top edge of bar 29 is supporting bar 41, and then moving the plunger inward again, such inward movement will be prevented by spring 72 forcing hook 71 down into hole 35 30 whereupon inward movement of the plunger unit will be prevented.

The insertion of a coin of less diameter than a nickel will be ineffective. Such coin will not 35 lift bar 41 and the top of bar 29 above notch 64 will strike the edge of bar 41 or the edges of wings 56 will strike the tubes. Either such contact will stop the inward movement of the plunger unit and, in any event, there will be nothing to lift the tubes or uncover any tablets. By reason 40 of the reciprocation of the plunger any effort to operate it, in such case, will cause the coin to roll down incline 67a and into the coin box 33 through hole 36.

In case all the tablets are exhausted and, notwithstanding the indication thereof by plug 49 45 viewed through window 26, an attempt be made to operate the machine with a nickel, damage to the machine is prevented by forming plug 49 with the conical base 50 so that when wings 56 50 strike the plugs they strike the cone shaped base and raise the plugs in the tubes and slide beneath the plugs.

The runners 58 raise the wings 56 sufficiently 55 to clear the gaskets 34 during reciprocation of the plunger unit.

For convenience in removing the dropped cup and also to prevent access to the nest of cups through opening 24, rake 75 is carried by and depending from shelf 57 so that when the plunger 60 unit is retracted the rake will shove the dropped cup forward toward opening 24 through which it may be manually removed, in which position the rake prevents reaching the nest of cups. Slide 65 76 may be provided to prevent catching of the cup on the housing edge at the bottom of opening 24. To hold the plunger unit in sliding alignment with and upon brackets 32b and 63 I provide complementary bracket 71 slidingly engaging the top of runner 58, and bracket 78 slidingly 70 engaging the top of lug 62 and the top of the wedge 60 directly in front of said lug 62.

In order to insure the alignment of the nest 75 of cups with the inner surfaces of guides 45 and 52 at all times, it is necessary only, in loading the machine, to place in the nest of cups three

cups in excess of the number of tablets in one of the tubes so that when the tablets have all been ejected there will still be three cups in the nest and the rim of the top cup will be within and in contact with the lower ends of guides 45 5 and 52, and the nest will thus be held in alignment within said guides all as clearly illustrated at Fig. 3.

When the machine is open, as illustrated at Fig. 3, a new nest of cups may be readily inserted 10 on shelf 57 and between the guides 45, 52 and 53 and upon closing the machine guide 54 will also contact the rims and form the fourth side of the run-way for the cups.

Likewise, when the machine is open, coin box 15 33 may be removed by sliding along brackets 32 and out from under shelf 31 for emptying, it being understood that the box has no cover except when in place beneath shelf 31 which then 20 covers the box.

The tubes may be removed for reloading by lifting them free of the gaskets, moving them 25 backward until they clear the rear of shelf 31, (the fit in guides 39 being sufficiently loose for this purpose) and then dropping the tubes out of guides 39. Caps 38 and the plugs 59 are removed and the tubes filled with new tablets through the tops, so that the older tablets will always be at the bottom. The plugs 59 and caps 30 38 are then replaced and the tubes placed in operative position on the gaskets by the reverse of the above described removing operation. The coin box is then slid into position and the machine closed and locked.

While I have shown and described details of 35 construction many changes may be made therein, as will be obvious to those skilled in the art, but all within the spirit and scope of the foregoing disclosure and the appended claims and I 40 do not wish to be confined to such details.

I claim:

1. In a vending machine in combination, a plurality of tablet-containing tubes interconnected by a bar, a reciprocable plunger including a stop normally contacting said bar to limit 45 reciprocation, a seat in said plunger adapted to seat a coin vertically with its horizontal diameter below but with its top above the edge of said bar whereby to raise said bar and tubes when the plunger is projected beneath the bar, wings on 50 said plunger adapted to remove tablets from beneath said tubes when the tubes have been raised, a shelf on said plunger adapted to normally support a nest of inverted cups but removable from under said nest by projection of said plunger 55 when said coin is seated therein and means carried by the plunger for supporting all of said cups above the bottom cup when said shelf is removed from under the nest.

2. In a vending machine, in combination, a 60 plurality of tablet-containing tubes interconnected by a bar and normally resiliently seated on gaskets, a reciprocable plunger including a stop normally contacting said bar to limit reciprocation, a seat in said plunger adapted to 65 seat a coin vertically with its horizontal diameter below but with its top above the edge of said bar whereby to raise said bar and said tubes when the plunger is projected beneath the bar, wings on said plunger adapted to move between the 70 gaskets and the lower ends of the tubes when the tubes are raised whereby to remove tablets resting on said gaskets.

3. In a vending machine, in combination, a 75 plurality of tablet-containing tubes intercon-

- 5 nected by a bar, a reciprocable plunger including a stop normally contacting said bar to limit reciprocation, a seat in said plunger adapted to seat a coin vertically to act as a cam to raise said bar and tubes when the plunger is projected beneath the bar, wings on said plunger positioned to slide beneath said tubes and remove tablets when the tubes have been raised and means for removing the coin from the seat after the coin has passed the bar.
- 10 4. In a vending machine, in combination, a plurality of tablet-containing tubes interconnected by a bar, a reciprocable plunger including a stop normally contacting said bar to limit reciprocation, a seat in said plunger adapted to seat a coin vertically to act as a cam to raise said bar and tubes when the plunger is projected beneath the bar, wings on said plunger positioned to slide beneath said tubes and remove tablets
- 15 20 when the tubes have been raised and means for removing the coin from the seat after the coin has passed the bar, and a catch operable when no coin is in the seat to prevent inward movement of the plunger.
- 25 5. In a vending machine, in combination a plurality of tablet-containing tubes interconnected by a bar, a reciprocable plunger having means for seating a coin in position to contact

and raise the bar and tubes and to remove tablets from beneath the raised tubes all by reciprocation of the plunger, said tubes being transparent and being enclosed in a housing provided with windows through which the tubes and contents are visible, plugs in said tubes having graduations thereon visible through said tubes and said windows whereby to indicate the number of tablets remaining in the tubes.

6. In a vending machine, in combination, a plurality of tablet-containing tubes, and a chamber containing a nest of inverted cups, a plunger comprising a shelf normally supporting said nest but removable from under the nest by projection of the plunger inwardly and means associated with said shelf for supporting all but the lower cup of the nest when said shelf is removed from under the nest, said plunger also including wings projectible beneath the tubes when the tubes are raised and a stop carried by the plunger normally 10 contacting a bar interconnecting the tubes to prevent inward movement of the plunger and means on the plunger to seat a coin vertically to act as a cam beneath said bar when the plunger is projected therebeneath whereby to raise said bar and 15 remove tablets from beneath said tubes by the forward movement of said wings.

GLEN G. BARNARD.
